By. *S. P. Orwaeel* Atty.

UNITED STATES PATENT OFFICE.

JAMES J. HENNESSY, OF NEW YORK, N. Y.

JOURNAL LUBRICATOR.

1,423,850.

Specification of Letters Patent. Patented July 25, 1922.

Application filed September 20, 1921. Serial No. 501,867.

To all whom it may concern:

Be it known that I, JAMES J. HENNESSY, a citizen of the United States, residing at New York city, New York, have invented a 5 certain new and useful Improvement in Journal Lubricators, of which the following is a full, clear, and exact description, such as will enable others skilled in the art to which it appertains to make and use the 10 same, reference being had to the accompanying drawings, forming part of this specification.

My invention relates to journal lubricators such as are used on railway rolling 15 stock, and consists in an improved lubricant receptacle and lubricant pumping mechanism.

The object of my invention is to provide 20 a cam operated pump which will be simple and effective and occupy a minimum amount of space on the car or locomotive journal.

An additional object of my invention is to provide means for preventing the splashing 25 of free lubricant from the lubricator well to the exterior of the lubricator.

In the accompanying drawings, illustrating a selected embodiment of my invention—

Figure 1 is a longitudinal section through 30 my lubricator shown in assembly with the journal and wheel hub of a railway car.

Fig. 2 is a transverse section through my lubricator taken on line 2—2 of Fig. 1.

Fig. 3 is a detail section on line 3—3 of Fig. 1.

The lubricator comprises a reservoir 1 which extends a substantial distance below the journal A with which it is assembled, and the lower portion of which forms a lubricant well 2. The bottom wall of the 40 reservoir has an integral pump cylinder 3 provided with check valves 4 and 5. A pump plunger 6 is slidably mounted in cylinder 3 and a horizontal plunger operating rod 7 is slidably mounted in the reservoir 45 and extends exteriorly thereof through the side wall of the reservoir. Plunger 6 and rod 7 are connected through a lever 8 which is pivoted to the reservoir at 9.

Positive driving means for the operating rod 7 is supplied by the rotating journal 50 through a collar 10 which may be clamped on the journal as shown and which is provided with a cam surface 11 having a short rise 12 adapted to contact with the outer end of rod 7 upon each revolution of the 55 journal. The inner end of rod 7 is engaged by a compression spring 13 which thrusts the rod outwardly whenever the latter is released by rotation of collar 10.

The reciprocating action of rod 7 reciprocates plunger 6 and alternately draws the lubricant into the pump cylinder 3 through valve 5 and discharges it upwardly therefrom through valve 4. Each of the walls of the reservoir are offset, as shown, to form 65 a seat for a waste pan 14, the walls of which are offset correspondingly. This seating of the waste pan in the reservoir prevents any splashing of the lubricant from the well to the outside of the reservoir. 70

The bottom of the waste pan is recessed at 15 to accommodate the pump cylinder and the operating mechanism.

I contemplate the usual modifications of my lubricator, without departing from the 75 spirit of the invention, as set forth in the following claim.

I claim:

In combination, a railway car journal, a journal lubricator including a waste receptacle held in contact with said journal, a lubricant reservoir adjacent to said receptacle, a pump for feeding lubricant from said reservoir to waste in said receptacle, a pump actuating rod extending parallel 85 with said journal exteriorly of said reservoir and receptacle, a cam mounted on said journal and contacting with said rod to move the latter axially in one direction with each revolution of the journal, and means 90 energized by such movement to return said rod to its original position.

In testimony whereof I hereunto affix my signature this 29th day of June, 1921.

JAMES J. HENNESSY.
